United States Patent Office.

IMPROVED BURGLAR ALARM.

WILLARD FARNHAM, OF JANEVILLE, WISCONSIN.*

Letters Patent No. 60,162, dated December 4, 1866.

SPECIFICATION.

TO ALL WHOM IT MAY CONCERN:

Be it known that I, WILLARD FARNHAM, of Janesville, in the county of Rock, and State of Wisconsin, have invented a new and improved Burglar Alarm; and I do hereby declare that the following is a full and exact description thereof, reference being had to the accompanying drawings, in which—

Figure 1 is an elevation or side view of my burglar alarm.

Figure 2 is a side view inverse to fig. 1.

Figure 3 is the same as fig. 1, but showing some of the parts in a different position.

Figure 4 is a front view; and

Figure 5 is a top view of the same.

The nature of my invention consists, first, in constructing a burglar alarm of the form of a wedge, with spurs or teeth in the bottom of the same, so that by placing it with its point under a door the latter is effectually prevented from being opened; second, in providing a burglar alarm, constructed as above, with a trip lever, tumbler, and spring, dog, hammer, nipple, and match-holder, so arranged that when placed in position under a door, the opening of the latter shall cause the hammer to ignite a cap and also to light a match.

To enable others skilled in the art to make and use my invention, I will proceed to describe its construction and operation.

I construct the supporting part, A, of the general form of a wedge, providing it with a suitable base, B B, to prevent it from being jostled over. To these I attach, as in an ordinary gun-lock, the tumbler and spring, C and D, hammer E, and nipple F. I also attach thereto, as shown in drawings, a trip lever G, dog H, and match-holder, I. The base, B B, has spurs or teeth, a a, projecting forward to catch or bite in the floor to prevent my device, when used as a door fastener, from being shoved out of position as the door opens. These spurs may be of any form and number, and placed in any desired position on the bottom of the base, B. I generally provide the dog, H, with an operating spring, c, working against a support, as the pin, d.

To operate my device, it is only necessary to raise the trip lever, G, and cock the hammer, E, when the parts will be in the position, as shown in figs. 1 and 2. Now, by placing a percussion cap on the nipple, F, and a sperm friction match (or any other good match) in the holder, I, and my device, so arranged, with the point, K, under or near the door desired to be secured, we are ready for the burglars; as, when the door is attempted to be opened, the bottom of it strikes upon or against the trip lever, G, driving it down and driving back the dog, H, thereby releasing the tumbler, C, and causing the spring, D, to drive the hammer, E, upon the cap, snapping it and thus producing an alarming noise, while the point, f, strikes the match, producing a light, so alarming the burglar and illuminating the room; the last is an important consideration, especially to the occupants of strange rooms. Besides the noise and light, the door is securely closed, as any attempt to open it only drives still farther the spurs or teeth, a a, into the floor.

What I claim as new, and for which I desire Letters Patent of the United States, is—

1. The combination and arrangement of the wedge A, base B B, and spurs a a, substantially as and for the purpose set forth.
2. The combination and arrangement of the wedge A, base B B, tumbler C, spring D, hammer E, dog H, and nipple F, substantially as and for the purpose set forth.
3. The combination and arrangement of the wedge A, base B B, tumbler C, spring D, hammer E, dog H, and match-holder I, substantially as and for the purpose set forth.

WILLARD FARNHAM.
